CLAIM

The ornamental design for a hydraulic power unit, as shown and described.

DESCRIPTION

FIG. 1 is a front perspective view of a hydraulic power unit showing the new design.

FIG. 2 is a top view of the hydraulic power unit of FIG. 1.

FIG. 3 is a bottom view of the hydraulic power unit of FIG. 1.

FIG. 4 is a first side view of the hydraulic power unit of FIG. 1.

FIG. 5 is a second side view of the hydraulic power unit of FIG. 1.

FIG. 6 is a third side view of the hydraulic power unit of FIG. 1; and,

FIG. 7 is a fourth side view of the hydraulic power unit of FIG. 1.

(Continued)

The broken line showing portions of the hydraulic power unit form no part of the claimed design.

1 Claim, 5 Drawing Sheets
